UNITED STATES PATENT OFFICE.

CHARLES W. CHENEY, OF BOSTON, MASSACHUSETTS.

MASSAGE APPLIANCE.

Application filed July 20, 1926. Serial No. 123,739.

This invention pertains to massage appliances and more particularly to rotary applicators of that type adapted to produce deep indentations in the flesh of the patient with intervening ridges or wrinkles which progressively advances as the applicator is rotated, thus breaking down fatty tissue.

Practical experience has demonstrated that highly beneficial results are obtainable when the flesh engaging surfaces of the applicators are hard and smooth as compared with pads of soft rubber, felt, etc., since such hard and polished surfaces permit the rapid movement of the applicator relative to the surface of the skin, which is essential to proper operation, but without injury to the patient, although at the same time forming the deep wrinkles essential to effective action. Heretofore I have employed applicator knobs of highly polished and hard steel with good results, but further experience has convinced me that higher efficiency is obtainable if the flesh engaging elements, although still hard and polished, are of some non-metallic material, which is a poor conductor of heat, such, for example, as wood.

Such non-metallic knobs have certain very important advantages due particularly to the fact that they are relatively poor conductors of heat and also because such materials produce a somewhat greater frictional effect on the skin than does metal.

When a metal knob is employed it is necessary to keep the applicator substantially at bodily temperature in the intervals between periods of use or to preheat it prior to use since the contact of the cold metal with the patient's skin causes a disagreeable shock. Furthermore, the metal knob conducts away heat from the skin surface so rapidly that the heat generated by the rubbing friction is insufficient to keep the applicator warm, so that it always feels cold to the patient's skin. Moreover, the polished metal surfaces produce but little friction even under high pressure and at high speeds of rotation, although for the most effective action it is desirable to produce considerable friction which has the effect of stimulating the circulation of the blood in the skin, thus assisting in carrying away the broken down tissue.

When the applicator knob is made of a wood or other polished non-metallic material which is a poor conductor of heat, the applicator may be kept at room temperature and

applied to the patient with little discomfort; more important, it produces an agreeable sensation of warmth to the skin when in operation, due to the frictional heat generated, and practical experience has convinced me that this frictional heating effect also stimulates the blood vessels of the skin.

Furthermore, such a non-metallic surface, even when highly polished appears to contact more intimately with the skin than does metal and thus to produce a more pronounced frictional effect on the skin than metal although without tearing or otherwise injuring the skin. Preferably I so mount the non-metallic flesh engaging member as to permit it to yield under excessive pressure and to avoid injury when passing over bony structures close beneath the surface of the skin. Since such a non-metallic member is subject to more rapid wear than is a hardened steel member, I prefer to provide for its ready replacement when worn.

The accompanying drawings show, by way of example, certain desirable embodiments of the invention, in which:

Fig. 1 is a side elevation of a massage apparatus provided with an applicator having knobs embodying the present invention;

Fig. 2 is a bottom plan view of the applicator shown in Fig. 1;

Fig. 3 is a diametral section illustrating one form of applicator knob and showing a fragmentary portion of the support or body of the applicator; and

Figs. 4, 5 and 6 are views similar to Fig. 3 but showing respectively modifications of the improved structure.

Referring to the drawings, numeral 1 designates a casing forming the body portion of the massage apparatus, such casing having a handle 2 and providing bearings for the applicator shaft 3. The casing is furnished with suitable gears, not shown, designed to transmit motion to the shaft 3 from the shaft 4 disposed substantially at right angles to the shaft 3. This shaft 4 is preferably flexible to permit proper manipulation of the apparatus and is driven by any suitable source of power.

The shaft 3 carries the applicator proper which, as shown in Fig. 1, comprises a base 5 preferably in the form of a disk which has a plurality of knobs 6 projecting from its end surface. These knobs may be spaced in any suitable manner but preferably symmetrically with respect to the axis of the

disk 5. A suitable arrangement is indicated in Fig. 2, it being noted that each of the knobs is arranged eccentric to the axis of the disk. Other arrangements of the knobs of 5 the disk may be used if desired.

In accordance with the construction shown in Fig. 3 the knob comprises an elongate cylindrical base member 7 attached at 8 to the disk 5. This base member is preferably 10 provided with an axially elongate diametral slot 9 and constitutes a guide for a sleeve 10 which telescopes over this base member. To limit the movement of the sleeve 10 outwardly away from the disk 5, I provide a 15 pin 11 extending through the slot 9 of the base member and having its opposite ends secured in the walls of the sleeve 10. This arrangement permits limited movement of the sleeve longitudinally of the base member. 20 The outer end of the sleeve 10 is closed by means of a plug 12. This plug is made of some hard non-metallic material which is a poor conductor of heat such, for example, as wood. Boxwood or similar close-grained 25 material is very desirable for the purpose, although I contemplate that other materials than wood may be substituted provided, they have the desired qualities of hardness and poor heat conduction. 30 The plug 12 is furnished with a neck 13 which fits within the outer end of the sleeve 10. The plug is held in place in the sleeve by means of a removable pin 14. By removing the pin the plug may be withdrawn from 35 the sleeve and replaced by another plug either of the same or different material. Thus I provide a ready means for varying the effect of the applicator by substituting plugs of various materials, while I also provide for ready replacement of worn plugs, such replacement being necessary at frequent 40 intervals since plugs made of wood or like substances wear quite rapidly when subjected to the friction of use. 45 The outer portion of the plug 12 is of substantially the same diameter as the outside diameter of the sleeve 10, and its outer end is smoothly rounded to provide a substantially semi-cylindrical rubbing surface 15. Preferably, this surface is polished and merges smoothly into the cylindrical surface 50 of the sleeve 10.

The inner end of the plug 12 is furnished with an axial socket 16 which is opposed to 55 a similar socket 17 in the outer end of the base 7. The opposite ends of a compression spring 18 are seated in the sockets 16 and 17 respectively. The spring 18 tends to force the sleeve 10 outwardly to the extent permitted by the stop member 11, but permits the sleeve to move inwardly when sufficient pressure is applied to the plug 12.

In Fig. 4 the disk member is indicated at 5^a, the base of the knob at 7^a, and the sleeve 60 which telescopes over the base at 10^a. The

base is provided with an elongate slot 9^a for the reception of the retaining pin 11^a whose opposite ends are seated in openings in the sleeve 10^a. This pin 11^a is removable and is normally held in operative position by 70 means of a spring ring 19.

The outer end of the sleeve 10^a is closed by a plug 12^a having a neck 13^a fitting within the sleeve and held in place by the removable pin 14^a. The plug has a spherically 75 curved outer surface 15^a and the sleeve 10^a is held in its normal position by means of the spring 18^a held in place around the member 7^a between the disk member 5^a and the base of the sleeve 10^a. 80

In Fig. 5 the disk 5^b supports the base member 7^b which, in this instance, has a neck portion 20 of reduced diameter. The sleeve 10^b telescopes over the base 7^b and is furnished at its inner end with an annular 85 collar 21 which encircles the neck portion 20 of the base and which engages a stop shoulder 22 on the base for limited outward movement of the sleeve.

The sleeve 10^b carries the plug 12^b at its 90 outer end, such plug having a neck 13^b held in place by the removable pin 14^b. The plug has a rounded surface 15^b and the spring 18^b is introduced between the inner end of the plug and the outer portion of 95 the base 18^b.

In Fig. 6 the disk 5^c is provided with spacer posts 23 which support a secondary disk 24 in spaced relation to the disk 5^c. The knob comprises the base member 7^c attached to the disk 5^c, and this base member constitutes a guide for the sleeve 10^c which telescopes over the base member 7^c, passing through an annular opening between the base member and the member 24. The outer 100 end of the sleeve 10^c is closed by a plug 12^c having a neck 13^c held in position by the removable pin 14^c. The outer end of the plug is smoothly rounded as shown at 15^c. The inner end of the plug is furnished with 105 a socket 16^c opposed to a socket 17^c in the base 7^c. A compression spring 18^c has its opposite ends seated in the sockets 16^c and 17^c. This spring tends to move the sleeve 10^c outwardly but this movement is limited by the engagement of a flange 25 at the inner 110 end of the sleeve with the inner surface of the member 24. 115

It being understood that applicator knobs of any of the types above described may be associated with one another in any desired combination upon the disk or support 5, it may be assumed that the shaft 3 is driven at the desired speed and that the outer ends of the several knobs carried by the disk 5 are applied to the flesh of the patient. These knobs, being of substantial length, may be pressed deeply into the patient's flesh, and when rotated produce deep indentations and wrinkles which progress rapidly as the ap- 120 125 130

plicator is rotated. Since the end portions of the applicator knobs are of material which does not conduct heat rapidly and which produces substantial friction when in engagement with the skin, the rapid rotation and movement of the knobs in contact with the skin creates a considerable amount of frictional heat, and as this heat can not flow away rapidly, a sensation of heat is produced which is not only agreeable to the patient but also apparently assists in creating rapid circulation through the blood vessels of the skin. The glow thus produced is highly advantageous both in its tonic effect on the skin and also because of the fact that the more rapid blood flow carries away the old or broken down tissue, and thus assists in the reducing action. While it is desirable to produce a certain degree of friction such as is, in fact, produced by highly polished wooden knobs or knobs of similar material, it is not desirable to increase the friction unduly as would be the case were soft knobs or pads employed, since the rapid rotation of such soft pads under the pressure which is desirable for flesh reduction would undoubtedly cause tearing or other injury to the skin which is, of course, not permissible.

Since knobs of wood or similar material wear quite rapidly, it is necessary to replace them from time to time which may readily be accomplished, in the arrangement herein illustrated, by removing the retaining pin which holds the knob in position within the socket sleeve.

While I have illustrated certain desirable forms of applicator knob as embodying the present invention, I wish it to be understood that in its broader aspects the invention is not necessarily limited to use in yielding knobs such as those herein disclosed nor to constructions in which the flesh engaging element is replaceable.

I claim:

1. In a mechanically operated massage appliance of the kind having a rotary supporting disk and a plurality of knobs projecting from one face of the disk, one at least of said knobs comprising telescoping cylindrical members, one of said members

being secured to the disk and the other having a removable end closure, said end closure consisting of a plug of hard non-metallic material having a substantially hemispherical flesh engaging surface.

2. In a mechanically operated massage appliance of the kind having a rotary support and a knob carried by the support, said knob comprising an elongate base member, an open ended metallic sleeve telescoping over said base member, a spring tending to move the sleeve outwardly from the support, a stop limiting such outward movement, and a removable wooden plug fitting within the outer end of the sleeve, said plug having a smooth and substantially hemispherical outer surface.

3. A mechanically operated massage applicator knob comprising a cylindrical base supported at one end, a cylindrical sleeve telescoping over said base, one of said parts having an axially elongate slot and the other having an element engaging said slot to limit relative movement of the parts, a non-metallic plug secured in the outer end of the sleeve, said plug having a hard and smoothly rounded outer surface, the inner end of the plug having a socket, and a compression spring having one end seated in said socket and the other seated in a socket in the outer end of the base.

4. A mechanically operated massage applicator knob comprising an elongate base member supported at one end, a sleeve telescoping over the base member, a spring tending to move the sleeve outwardly away from the supported end of the base member, stop means to limit outward movement of the sleeve, a plug closing the outer end of the sleeve, said plug having a stem fitting within the sleeve, and a head of a diameter substantially equal to the outside diameter of the sleeve, said head being of hard non-metallic material and having a smoothly rounded outer end, and a removable pin for retaining the plug in the end of the sleeve.

Signed by me at Boston, Massachusetts, this 19th day of July, 1926.

CHARLES W. CHENEY.
